UNITED STATES PATENT OFFICE

2,068,670

AUTOMATIC MIXER CONTROL SYSTEM

Maurus T. Goetz, Chicago, Ill., assignor to Teletype Corporation, Chicago, Ill., a corporation of Delaware

Application June 22, 1935, Serial No. 27,865

23 Claims. (Cl. 199—20)

This invention relates to linecasting and composing machines and particularly to the shifting of the magazines of multi-magazine composing machines by an automatically controlled unit responsive to prearranged signals.

For convenience in describing the present invention, the standard structure of a well-known commercial linecasting and composing machine, as illustrated in the accompanying drawing, will be referred to hereinafter as the principal machine, while the mechanism which is operative for initiating the magazine shifting function of the principal machine will be referred to hereinafter as the control unit.

An object of the invention is to provide control means responsive to selectable elements under the control of stored signals for the magazine shifting mechanism of standard linecasting machines.

The invention features an arrangement for rendering the control unit non-responsive to repeated identical magazine shift signals.

In multiple magazine linecasting machines any one of the two or more matrix storage magazines may be rendered capable of delivering matrices by establishing operative relation between the magazine and a set of matrix selecting lever systems. Such establishment of relationship may be described as qualifying the magazine for operation, since there is conferred upon the magazine a quality which enables it to perform the function for which it is provided, namely, to discharge matrices.

Briefly, the invention includes mechanical means for depressing the magazine shift key of a standard commercial linecasting and composing machine and thereby automatically starting into operation a magazine shifting mechanism of the linecasting machine. When the magazine shift operation has been substantially completed, the shift key is permitted to return to its unoperated position and the control unit is rendered unable to respond to a like magazine shift signal. A different magazine shift signal will then be effective upon the control unit to effect the depression of the magazine shift key to operate the magazine shifting mechanism whereby the magazines are restored to their previous operative condition. Thus successive different shift signals will alternatively condition the magazines, but successive identical magazine shift signals will not operate the magazine shifting key.

For a complete understanding of the invention, reference may be had to the following description and to the accompanying drawing in

which the single figure represents schematically in perspective a control unit having embodied therein the subject matter of the invention as applied to the magazine shifting mechanism of a standard commercial linecasting machine. 5

In the drawing, only so much of the mechanism of the principal machine has been shown as is deemed necessary to disclose clearly the cooperation of the control unit therewith. For a full and complete understanding of one form of 10 selecting means which may be employed for initiating the operation of the control unit which forms the subject matter of this invention, reference may be had to Patent No. 2,036,282, 15 granted April 7, 1936 to E. S. Larson.

Principal machine

Referring now to the drawing, the reference numeral 10 designates a pair of matrix storage magazines of a standard commercial linecasting 20 and composing machine. The magazines may be supported at the rear edges thereof by pivots (not shown) and the upper magazine may be supported above the lower magazine in the usual way so that the two magazines may be shifted 25 as a unit. A bracket 11, having a downwardly extending arm 12, is provided for supporting the magazines adjacent the front edges thereof and at the lower end of the arm 12 is secured a transversely extending pivot pin 13. A toggle 30 lever system consisting of the levers 14 and 16 connects the bracket 11 to a portion 17 of the stationary frame of the linecasting machine, there being a pivot pin 18 secured to the frame portion 17 for pivotally securing the lower end 35 of the lever 16. The upper end of the lever 14 pivotally engages the pivot pin 13, and the adjacent ends of the levers 14 and 16 are pivotally connected together by the common pivot 19 which has an extension slidably in a slot 21 in the frame portion 17 for guiding and limiting the movement of the toggle lever system. 40

A bell crank lever 22, which is pivotally mounted on a fixed pivot 23, has one end operatively engaging the pivot pin 19 to operate the toggle lever system and has its other end connected by a link 24 to a crank pin (not shown) carried by a rotatable cam member 26. The rotatable member 26 is fixed to a rotatable shaft 27 which is driven through the medium of bevel gears 28 and 29, shaft 31, and friction clutch 32, from a worm gear 33 to which rotation may be imparted by a worm 34. The worm 34 is loosely mounted on a shaft 36, which may be any power driven shaft of the principal machine such as the so- 50 55

called intermediate shaft. The loose mounting of the worm 34 permits the shaft 36 to rotate independently of the worm, and the shaft has secured thereto in spaced relation to the worm 5 34 a bevel gear 37.

A clutch sleeve 38 is loosely and slidably mounted on the shaft 36 intermediate the worm 34 and the gear 37 and the sleeve 38 has positive driving connection with the worm 34 through 10 the medium of leftwardly extending fingers 39, which are disposed within slots 41 in the hub of the worm 34. At its opposite end, the sleeve 38 is provided with teeth 42 which may be brought into engagement with recesses 43 formed in the 15 hub of beveled gear 37 to permit the establishment of driving connection between the beveled gear 37 and the worm 34 when the clutch sleeve 38 is shifted rightwardly. The sides of the teeth 42 are preferably disposed obliquely with respect 20 to the faces thereof and the recesses 43 are correspondingly formed, as shown in the drawing, so that when the clutch sleeve is brought into engagement with the hub of the rotating bevelled gear 37, a mutual camming action between the 25 teeth 42 and recesses 43 creates a continuing tendency for the clutch sleeve to be forced out of engagement. Thus the clutch always seeks disengagement unless restrained therefrom, and means, presently to be described, is provided for 30 so restraining the clutch during intervals in which its continued engagement is desired.

A clutch yoke 44 engages the clutch sleeve 38 and is connected to a lever 46 mounted on a rock shaft 47 by means of a pin 48. At the opposite end of the rock shaft 47 from the lever 46 there is secured a lever 49 which has pivotally depending from the outer end thereof a link 51. A push rod 52 is positioned below and in alignment with the link 51, and a keylever 53 which 40 is pivotally supported at 54 pivotally engages the push rod 52 by means of the pivot pin 56. The keylever 53 is provided with a finger key 55.

In order to insure the completion of a magazine shift after it has been initiated, the rotatable 45 cam member 26 which operates the link 24 is provided on its opposite face with diametrically opposed recesses 57. A lever 58, pivotally mounted at 59, has one end thereof engaging the clutch yoke 44 and the other end terminating in a portion 61 which may enter a recess 57.

The operation of the disclosed part of the principal machine is as follows: When the magazines are to be shifted, the finger key 55 is depressed, which causes the keylever 53 to rock on 55 the pivot 54 and raise the push rod 52 upwardly. The push rod 52 reciprocates the link 51, thus rotating the lever 49 and rocking the shaft 47 to cause the teeth 42 on the clutch sleeve 38 to engage the hub of the continuously rotated 60 bevel gear 37, and thus drive the worm 34. The rotation of the latter causes the worm gear 33 to be driven and through the medium of elements previously described the member 26 is rotated and the link 24 is thereby caused to rotate 65 the bell crank lever 22. The bell crank lever 22 may be rotated counterclockwise from the position shown in the drawing and this causes the pivot pin 19 to travel to the opposite end of the guide slot 21 and rotates the lever 16 counterclockwise on its pivot pin 18 to lower the magazines 70 10 by drawing downwardly on the lever 14.

Since the lever 58 is connected to the clutch yoke 44, the shifting of the clutch yoke to cause engagement of the clutch results in a counterclockwise rotation of the lever 58 about the 75

pivot 59. This rotation of the lever 58 causes the portion 61 of the lever to be withdrawn from a recess 61 in the face of the rotatable cam 26. As cam 26 rotates, the lever 58 is blocked from clockwise rotation by the engagement of the portion 61 of the lever with the face of cam 26. When cam 26 has completed one-half revolution, which occurs at the completion of a magazine shift, a recess 57 is brought into alignment with the portion 61 of the lever 58, so that that portion 10 may enter the recess, thus permitting the clutch to become disengaged by a leftward movement of the clutch sleeve 38 under the influence of the mutual camming action of the teeth 42 and recesses 43. 15

Control unit

The reference numeral 62 designates a set of code bars which are adapted to selectively condition the code levers 63 and 64. The code bars 20 are responsive to stored signals in a manner fully described in the above identified patent, and a complete understanding of the manner in which the selective conditioning of the selectable code levers 63 and 64 is accomplished may be obtained by reference to the patent. It is deemed sufficient to state here that the code bars 62 are capable of a slight endwise reciprocatory motion and that the selective conditioning of the code levers 63 and 64 occurs when the code bars 62 25 assume certain predetermined positions. Upon the selective conditioning of either of the code levers 63 and 64, it is reciprocated rightwardly by a function performing bail not shown. 30

Levers 66 and 67 pivoted at 68 engage the code 35 levers 63 and 64 respectively, so that upon the rightward reciprocation of one of the code levers, its cooperating lever 66 or 67 is rotated in a clockwise direction. The levers 66 and 67 are normally urged in a counterclockwise direction by 40 the springs 69 and 70 respectively.

Adjacent to the left-hand end of the levers 66 and 67, a T-shaped member 71 which has slots 72 in the shank portion thereof is slidably mounted upon the fixed pins 73. At the left-hand end of the shank of the member 71 is mounted a pin 74 which is disposed within a slot 76 of a lever 77. The lever 77 is fixed to a shaft 78 which may be journaled in any convenient fixed portion of the principal machine and which has secured to its opposite end a lever 79 which is provided at its forward end with a downwardly extending portion 81, the lower end of which is disposed in alignment with and preferably a small distance above the finger key 55. 55 Adjacent to the lower end of the lever 77 is a bell crank lever 82 which constitutes a latch and which is pivoted at 83. The bell crank lever 82 is provided with a shoulder 84 behind which the lower end of the lever 77 may be retained after 60 the lever 77 is rotated in a clockwise direction as a result of the leftward movement of the T-shaped member 71. A spring 86 urges the bell crank lever 82 in counterclockwise direction into engagement with the lower end of the lever 77, 65 a spring 87 urges the lever 77 in counterclockwise direction, and a spring 88 urges the member 71 rightwardly, the springs 87 and 88 normally maintaining the end 81 of lever 79 from operative engagement with the finger key 55. 70

The arms of the T-shaped lever 71 are provided with slots 91 in which are disposed pins 92 carried by a reciprocable member 93. The member 93 is thus supported by the T-shaped lever 71 and is provided with rightwardly ex- 75

tending portions 94 which are spaced apart a distance different from the distance between the left-hand ends of the levers 66 and 67, so that one of the projections 94 may be aligned with 5 the end of one of the levers 66 and 67 in each of the limiting positions of the reciprocable member 93, as determined by the slots 91. A lever 95 which is pivoted at the fixed point 96, has one end pivotally engaging the reciprocable 10 member 93 at 97 and the other end pivoted at 98 to a link bar 99 which is pivotally associated with the magazines 10 to be moved upwardly or downwardly as the magazines are so moved. The link bar 99 is provided with a hump or cam portion 101 and the upper end of the bell crank lever or latch 82 is provided with a cam projection 102 disposed in the path of the cam portion 101 of the link bar 99.

The operation of the control unit is as follows: 20 Since the lower portion 94 of the reciprocable member 93 is in alignment with the left-hand end of lever 66, it will be assumed that a pre-determined stored signal has actuated the code bars 62 to condition selectively the code lever 63. The rightward movement of the code lever 63 under the influence of an operating bail (not shown), will cause the lever 66 to be rotated clockwise and its left-hand end will move leftwardly the lower element 94 of the reciprocable 25 member 93 which, by reason of the disposition of the pins 92 in the slots 91, will cause the T-shaped member 71 to slide leftwardly upon the pins 73. The pin and slot connection of the member 71 with the lever 77 will cause the latter 30 to be rocked clockwise, and as the lower end of the lever 77 moves behind the shoulder 84 of the latch 82, the latter will be rocked counterclockwise by its spring 86 to retain the lever 77 in the position into which it has been rotated. The 35 rotation of the lever 77 causes the shaft 78 to rock in clockwise direction, which carries the end 81 of the lever 79 into engagement with the finger key 55 and causes the depression of the finger key and thus the actuation of the keylever 40 53. The actuation of the keylever 53 will cause the magazine shifting mechanism of the principal machine to operate in the manner previously described. Since the magazines have been shown in their uppermost position, the 45 operation of the magazine shifting mechanism in response to the selective conditioning of the code lever 63 will cause the magazines to be lowered to their lowermost position.

The downward movement of the magazines 50 causes the link bar 99 to be moved downwardly, and an upward movement is transmitted to the reciprocable member 93 through the agency of the lever 95. As the reciprocable member 93 moves upwardly, the lower projection 94 is moved 55 out of alignment with the lever 66 and the upper projection 94 is moved into alignment with the end of lever 67. It is apparent from this description that should the code lever 63 again be selectively conditioned in response to a repeated signal, the magazine shifting mechanism would not be affected, for the reason that the lower projection 94 of the member 93 would be 60 out of operative alignment with the lever 66. This arrangement prevents the magazine shifting mechanism from responding to repeated identical magazine shifting signals and insures the alternative conditioning of the magazines in response to the proper predetermined signals only.

70 The restoration of the magazines to the posi-

tion shown in the drawing, after a shift operation as described in the foregoing paragraphs, is accomplished by causing the code lever 64 to be selectively conditioned in response to a pre-determined signal which differs from the signal 5 to which the code lever 63 is responsive. The selective conditioning of the code lever 64 results in a clockwise rotation of the lever 67, which, through the operative alignment of the upper projection 94 therewith, will cause the T- 10 shaped member 71 to slide upon the pins 73, thus rotating the lever 77, shaft 78 and lever 79 to effect the depression of the keylever 53. The depression of the keylever 53 causes the magazine shifting mechanism of the principal machine 15 to operate in the manner previously described, whereby the cam member 26 is rotated through one-half revolution to rotate the bell crank lever 22 clockwise by means of the link 24 and thus the magazines 10 are returned to their 20 uppermost position.

The upward movement of the magazines is accompanied by an upward movement of the link bar 99, and a clockwise movement of the lever 95. The member 93 is moved downwardly upon the 25 clockwise movement of the lever 95, bringing the lower projection 94 into alignment with the lever 66 and withdrawing the upper projection 94 from alignment with the lever 67.

In addition to shifting the reciprocable member 93 as outlined in the preceding paragraph, the downward or upward movement of the link bar 99 causes a clockwise rotation of the latch 82 by reason of the engagement of the cam portion 101 with the portion 102 at the upper end of the 30 latch 82. Upon the clockwise rotation of the latch 82, the lever 77 is released from engagement with the shoulder 84 thereof and is enabled to respond to its spring 87 to rotate counterclockwise and thus release the finger key 55. The 35 spring 88 cooperates with the spring 87 in releasing the lever 77, and the springs also cooperate in returning the T-shaped lever 71 to its normal or inoperated position.

Although a particular embodiment of the invention has been shown in the drawing and described in the specification, it is to be understood that the invention is not limited to the specific structure disclosed, but that it is capable of modification, rearrangement, or substitution of elements and operations without departing from the spirit of the invention and within the scope of the appended claims.

What is claimed is:

1. In an automatic control apparatus, devices to be qualified for operation alternatively, means for qualifying the devices, means responsive to signals for controlling the qualifying means, and means for rendering the signal responsive means 55 non-responsive to successive identical signals.

2. In an automatic control apparatus, devices to be qualified for operation alternatively, means for qualifying the devices, means responsive to coded signals for controlling the qualifying means, and means actuated during the qualifying 60 of the devices for rendering the signal responsive means non-responsive to successive identical signals.

3. In an automatic control apparatus, devices 70 to be qualified for operation alternatively, means for qualifying the devices, means responsive to coded signals for controlling the qualifying means, and means operatively associated with the devices to be qualified for rendering the sig- 75

nal responsive means non-responsive to successive identical signals.

4. In an automatic control apparatus, devices to be qualified for operation alternatively, means for qualifying the devices, means responsive to coded signals for controlling the qualifying means, means for latching the controlling means in operated condition, and means operatively associated with the devices to be qualified for releasing the latching means.

5. In an automatic control apparatus, devices to be qualified for operation alternatively, means for qualifying the devices, means responsive to coded signals for controlling the qualifying means, means for latching the controlling means in operated condition, and means operatively associated with the devices to be qualified for releasing the latching means and for rendering the signal responsive means non-responsive to successive identical signals.

6. In a linecasting and composing machine, a plurality of matrix storage magazines to be alternatively qualified for operation, means for qualifying the magazines, means responsive to a plurality of different signals for controlling the qualifying means, and means for simultaneously rendering the controlling means responsive to one signal and non-responsive to a different signal.

7. In a linecasting and composing machine, a plurality of matrix storage magazines to be alternatively qualified for operation, means for qualifying the magazines, single means for initiating the operation of the qualifying means, means responsive to coded signals for actuating the said single means, and means for preventing the actuation of said single means in response to successive identical signals.

8. In a linecasting and composing machine, a plurality of matrix storage magazines to be qualified for operation alternatively, means for qualifying the magazines, means for initiating the operation of the qualifying means, means responsive to coded signals for actuating the initiating means, and means for maintaining the initiating means operated during the qualifying of the magazines.

9. In a linecasting and composing machine, a plurality of matrix storage magazines to be qualified for operation alternatively, means for qualifying the magazines, means for initiating the operation of the qualifying means, means responsive to coded signals for actuating the initiating means, means for maintaining the initiating means operated during the qualifying of the magazines, and means operatively associated with the magazines for conditioning the initiating means for restoration to unoperated condition.

10. In a linecasting and composing machine, a plurality of matrix storage magazines to be qualified for operation alternatively, means for qualifying the magazines, a plurality of signal responsive elements, means for controlling the magazine qualifying means, and means for associating the controlling means with the signal responsive means alternatively.

11. In a linecasting and composing machine, a plurality of matrix storage magazines to be qualified for operation alternatively, means for qualifying the magazines, means for initiating the operation of the qualifying means, means responsive to coded signals for selecting one of a plurality of elements, means for actuating the initiating means, and means for associating the initiating means with the elements alternatively.

12. In a linecasting and composing machine, a plurality of matrix storage magazines to be qualified for operation alternatively, means for qualifying the magazines, means for initiating the qualifying means, means responsive to coded signals for operating a plurality of elements, means for actuating the initiating means, and means operatively connected to the magazines for associating said initiating means with said elements alternatively.

13. In a linecasting and composing machine, a plurality of matrix storage magazines to be alternatively qualified for operation, means for qualifying the magazines, single means for initiating the qualifying means, means responsive to coded signals for selectively operating a plurality of elements, means for operating the initiating means, means for maintaining the initiating means in operated condition, and means operatively connected with the magazines for associating said initiating means with said elements alternatively and for conditioning said initiating means for return to inoperative condition.

14. In a linecasting and composing machine, a plurality of matrix storage magazines to be qualified for operation alternatively, means for qualifying the magazines, a code bar responsive to coded signals, a lever selectively responsive to the code bar, a reciprocable member alternatively associated with the levers, means associated with the member for controlling the qualifying means, and means operatively associated with the magazines for controlling the association of the reciprocable member with the latter.

15. In a linecasting and composing machine, a plurality of matrix storage magazines to be qualified for operation alternatively, means for qualifying the magazines, a code bar responsive to coded signals, a plurality of levers selectively responsive to the code bar, a reciprocable member alternatively associated with the levers, means associated with the member for controlling the qualifying means, a link bar operatively associated with the magazines, and means connecting the link bar with the reciprocable member for reciprocating the member.

16. In a linecasting and composing machine, a plurality of matrix storage magazines to be qualified for operation alternatively, means for qualifying the magazines, a code bar responsive to coded signals, means for initiating the operation of the qualifying means, means selectable by the code bar for operating the initiating means, a latch for maintaining the initiating means in operated condition, a link bar operatively associated with the magazines, and means carried by the link bar for releasing the latch.

17. In a linecasting and composing machine, a plurality of matrix storage magazines to be qualified for operation alternatively, means for qualifying the magazines, a plurality of code levers, means responsive to coded signals for operatively conditioning the code levers, a reciprocable member alternatively associated with the code levers, means for initiating the operation of the qualifying means, means for connecting the reciprocable member to the initiating means for qualifying the magazines in response to coded signals, means for latching the initiating means in operated condition, a link bar operatively associated with the magazines, means carried by the link bar for releasing the latch, and means connecting the link bar with the reciprocable member for moving the reciprocable member to transfer the

- operative association of said member from one code lever to another.
18. In a linecasting and composing machine, a plurality of matrix storage magazines to be qualified for operation alternatively, means for qualifying the magazines, a code bar responsive to coded signals, a plurality of code levers selectively responsive to the code bar, a reciprocable member alternatively associative with the code levers, means for initiating the operation of the qualifying means, means connecting the reciprocable lever to the initiating means for operating said initiating means, a latch for maintaining the initiating means in operated condition, a link bar connected to the magazines, a cam-like projection carried by the link bar for releasing the latch to condition the initiating means for restoration to unoperated condition, and a lever connecting the link bar to the reciprocable lever for transferring the operative association of the reciprocable member from one code lever to another.
19. In an automatic control apparatus, a plurality of code selector bars to be permutatively positioned in accordance with a code system, a pair of selectable elements individually conditioned by said bars, a common actuator for receiving motion from said elements, and means for shifting said actuator to align it with said elements alternately.
20. In an automatic selector mechanism, a set of code bars permutatively positioned in accordance with a code system, a plurality of selectable ele-

ments individually conditioned in accordance with the disposition of said bars, a common actuator intermediate said elements and said member, and means for aligning said actuator with each of said elements successively.

21. An automatic actuating apparatus for a keyboard mechanism including a keylever, a mechanism initiated into the operation by the actuation of said keylever, signal controlled means for actuating said keylever, and latching means for prolonging the actuation of said keylever by said signal controlled means under the supervision of said mechanism.

22. In an automatic control apparatus, a plurality of actuators parallelly aligned in spaced relation with each other, a common motion recipient transversely disposed with respect to said actuators, projections associated with said common motion recipient having spaced relation with respect to each other differing from said spaced relation of said actuators, and means for shifting said common motion recipient so as to associate said projection with said actuators singly.

23. In a machine of automatic operation, a device to be shifted to alternate positions, a pair of actuators responsive to associated control signals for supervising the shifting of said device, means to which the supervision is transmitted, and means to align the last mentioned means with the actuators under the control of a predetermined condition of said device.

MAURUS T. GOETZ.
